UNITED STATES PATENT OFFICE.

GEORGE A. WEBER, OF NEW YORK, N. Y., ASSIGNOR TO WEBER RAILWAY JOINT MANUFACTURING COMPANY, OF NEW YORK, N. Y., A CORPORATION OF WEST VIRGINIA.

INSULATED RAIL-JOINT.

SPECIFICATION forming part of Letters Patent No. 772,985, dated October 25, 1904.

Application filed June 8, 1904. Serial No. 211,604. (No model.)

To all whom it may concern:

Be it known that I, GEORGE A. WEBER, a citizen of the United States, and a resident of the borough of Manhattan, city, county, and State 5 of New York, have invented certain new and useful Improvements in Insulated Rail-Joints, of which the following is a specification accompanied by drawings.

This invention relates to insulated rail-joints; and one of its objects is to insulate the rails one from the other and hold the rail ends in position under the passage of the train in such manner that the ends of the rails are prevented from moving upward when the wheels 15 are passing from one rail to another.

Another object of the invention is to secure a downward hold upon the base-flanges of the rails, but at the same time take a firm upward pressure under the heads.

Further objects of the invention will hereinafter appear; and to these ends the invention consists of a rail-joint for carrying out the above objects embodying the features of construction substantially as hereinafter fully 25 described and claimed in this specification, and shown in the accompanying drawings, in which—

Figure 1 is a transverse sectional view of an insulated joint embodying the invention. 30 Fig. 2 is a transverse sectional view of an insulated joint having a strip or block of fiber in place of the wooden filling-block on the inside of the joint. Fig. 3 is a plan view of Fig. 1. Fig. 4 is a side elevation of the joint looking at the outside of the upright of the shoe-angle. Fig. 5 is a side elevation of a joint embodying the invention with a fiber insulating-plate under one rail and a metallic plate under the other rail. Fig. 6 is a side elevation 35 of a joint embodying the invention, showing the metallic strut in two pieces instead of a continuous strut extending across the joint. Fig. 7 is a transverse sectional view of a modified form of joint having wooden filling-blocks 40 at each side of the rails, one of said blocks being provided with reinforcing metallic struts. Fig. 8 is a side elevation of the joint shown in Fig. 7.

Referring to the drawings, A and B represent the rail ends, and C is a rail-chair having a base D, an upright E, and a spiking rib or flange F. The upper end of the upright E, as shown, is provided with a head G, forming a hook turned inwardly toward the rails. On the side of the joint toward the upright 55 E a strut or struts H are provided, extending between the head or hooked end G of the chair and the base-flanges of the rails. In this instance the strut H is shown bearing upon insulation I, arranged along the angle between 60 the base-flanges of the rails and the web portion. By providing the insulation I electric continuity between the rails and the chair is prevented through the strut H. The strut H may consist of one continuous metallic bar extending across the joint, as shown in Figs. 4 and 5, or it may be broken, as shown in Fig. 6, and consist of the two parts H'. At the other side of the joint, opposite the upright of the chair, suitable insulating material is provided adjacent the webs of the rails. This insulating material may consist of a block of wood J, as shown in Fig. 1, or it may consist of a strip or block of insulating material K, as fiber, as shown in Fig. 2. Preferably a 70 continuous metallic strap or band L is provided, extending across the joint on the inside, and suitable bolts O secure the parts of the joint together.

Suitable insulation is provided for insulating one rail from the other, as shown, the usual insulating-sleeves P and washers Q being provided for the bolts where they pass through the strap L. Insulating-washers Q are also provided at the nut ends of the bolts, 85 and the insulating-sleeves R at this side of the joint are shown of such length that they serve to insulate the bolts from the upright of the chair and also insulate the metallic strut or struts H from the bolts. It is understood 90 that a sufficient number of the bolts are insulated in the manner described to break the electric continuity of the rails.

Suitable insulation S is provided beneath the base of at least one of the rails. In Fig. 95 4 the insulating fiber S is shown extending

under both rails, while in Fig. 5 the sheet of fiber S is shown under one rail, while a metallic plate T, preferably of steel, is arranged under the other rail. Preferably the steel plate T is placed under the receiving-rail.

Suitable means are provided for maintaining the insulation S beneath the rails, as shown in this instance, a piece of tape U, preferably of insulating material, being suitably secured to the fiber insulation S and then clamped between portions of the joint. Preferably the piece of tape U is interlaced with the fiber insulation S, as shown in Fig. 1. An air-gap may be left between the meeting faces of the ends of the rails; but preferably fiber end posts V are provided to maintain the rail ends out of contact.

In Fig. 7 a modification is shown in which an insulating-block W is substituted in place of the strut H. (Shown in Fig. 1.) This insulating-block W is preferably of wood and is provided at intervals with metallic struts X in the form of short rods or bars of iron or steel. In order to prevent electric connection through the metallic struts or strengthening-pieces X, they are preferably provided with insulating material Y, arranged between the two portions of each strut. The inwardly-turned head or hook portion G of the upright E of the chair bears upon the upper portion of the insulating-block W, and when the bolts are tightened it will be seen that the insulating-block is forced down upon the base-flanges of the rails and at the same time an upward pressure is produced under the heads of the rails. The metallic filling-pieces or struts X take the direct pressure between the head of the rail-chair and the base-flanges and prevent the wood from crushing, at the same time producing a strong downward pressure upon the base-flanges.

According to this invention it will be seen that a strong downward pressure is secured upon the base-flanges of the rails, which tends to prevent the rail ends from rising or moving upward when the wheels are passing from one rail to another. As shown in Figs. 7 and 8, an upward pressure is also obtained under the heads of the rails, which prevents the rail ends from sinking as the wheels are passing.

In all of the figures side bars are used at each side of the rails. These side bars are embodied in the wooden filling-blocks used, and they are also embodied in the continuous strap L, and the strut or struts H for the wooden filling-blocks may be termed "side" bars as well as the metallic side bars. The construction of the rail-chair is such that one of the side bars, whether of metal or insulating material, is locked to the base-flanges of the rails.

The chair of the construction described and shown in the drawings is constructed to secure a fit between the parts of the joint and the bearing-surfaces of the rails. These bear-

ing-surfaces comprise the under portions of the heads, the tops of the base-flanges, and the under portions of said flanges, whereby one of the side bars is locked to the base-flanges and produces a pressure thereon, while at the same time an upward pressure is produced beneath the heads of the rails. According to the arrangement of the struts it will be seen that both a downward and an inward pressure is produced upon the base of the rails. The force acting inwardly tends to maintain the rails in alinement.

Obviously some features of this invention may be used without others, and the invention may be embodied in widely-varying forms.

Therefore, without limiting the invention to the constructions shown and described nor enumerating equivalents, I claim, and desire to secure by Letters Patent, the following:

1. An insulated joint, comprising rails and side bars, and a rail-chair constructed to bear upon the upper portion of one of the side bars and produce a downward pressure on the base-flanges of the rails when the joint is tightened, and at the same time cause an upward pressure under the heads of the rails, and suitable insulation for preventing the electric continuity of the rails.

2. An insulated rail-joint, comprising rails and side bars, and a rail-chair constructed to bear upon the upper portion of one of the side bars and secure a fit between the parts of the joint and the bearing-surfaces of the rails, comprising the under portions of the heads, the tops of the base-flanges, and the under portions of said flanges, whereby one of the side bars is locked to the base-flanges and produces a pressure thereon, while at the same time an upward pressure is produced beneath the heads of the rails, and suitable insulation for insulating one rail from the other.

3. An insulated rail-joint, comprising rails and side bars, and a rail-chair constructed to bear upon the upper portion of one of the side bars and produce a downward pressure upon the base-flanges when the joint is tightened, and suitable insulation for insulating one rail from the other.

4. An insulated rail-joint, comprising the rails, a strap at one side of the joint, and a strut at the other, and a rail-chair constructed to force said strut against the base-flanges, and insulation for insulating one rail from the other.

5. An insulated rail-joint having a rail-chair with a hooked end on the upright, a strut between said hooked end and the base-flanges, and suitable insulation for breaking the electric continuity of the rails.

6. An insulated rail-joint, comprising rails and side bars, and a rail-chair comprising a base and an upright, said chair being constructed to bear upon the upper portion of one of the side bars and produce a downward pressure thereon when the joint is tightened,

and suitable insulation for insulating one rail from the other.

7. An insulated rail-joint, comprising the rails and side bars, a rail-chair constructed to 5 secure a downward pressure upon the upper portion of one of said bars when the joint is tightened, and insulation for insulating one rail from the other.

8. An insulated rail-joint, comprising the 10 rails and side bars, a rail-chair constructed to bear upon the upper portion of one of the side bars and to produce a downward and inward pressure on said bars, and insulation for insulating one rail from the other.

15 9. An insulated rail-joint, comprising rails and side bars, a rail-chair having a base for supporting the rails, an upright, and an inward extension from said upright, whereby the rails and one side bar are clamped between 20 the base and the extension of the upright of the chair, and insulation for insulating one rail from the other.

10. In an insulated rail-joint, the combina-

tion with the rails and suitable insulation, of a rail-chair having a hooked head forming an 25 inward extension for aiding in holding the parts of the joint together.

11. A rail-joint, comprising the rails, a rail-chair having an inwardly-turned hooked head, 30 a bar arranged between said hooked head and the base-flanges, bolts for securing the parts of the joint together, means for insulating said bolts from the bar and chair, and means for preventing short-circuiting through the bar.

12. An insulated rail-joint, comprising the 35 rails, filling-blocks at each side of the joint, a rail-chair having a head adapted to bear upon the top of one of the filling-blocks, and metallic filling-pieces in said block forming struts.

In testimony whereof I have signed this 40 specification in the presence of two subscribing witnesses.

GEORGE A. WEBER.
